US0D1066826S

(12) **United States Design Patent** (10) **Patent No.:** **US D1,066,826 S**
(45) **Date of Patent:** **** Mar. 11, 2025**

(54) **TABLETOP WITH A GRAPHIC DISPLAY**

(71) Applicant: **G&G Distribution, Inc.**, Phoenix, AZ
(US)

(72) Inventors: **Lori Haraske**, Boston, MA (US);
Michelle Austin, Phoenix, AZ (US)

(73) Assignee: **G&G Distribution, Inc.**, Orange, CA
(US)

(**) Term: **15 Years**

(21) Appl. No.: **29/738,467**

(22) Filed: **Jun. 17, 2020**

(51) **LOC (15) Cl.** **30-99**

(52) **U.S. Cl.**

USPC **D30/158**

(58) **Field of Classification Search**
